WRINGER

Walter L. Kauffman, II, Erie, Pa., assignor to
Lovell Manufacturing Company, Erie, Pa., a
corporation of Pennsylvania

Application May 11, 1933, Serial No. 670,462

3 Claims. (Cl. 68—32)

Power wringers have as an element of danger the possibility of the operator being caught between the wringer rolls. To alleviate this difficulty it is common with such wringers to supply what is known as safety release devices which instantly relieve the pressure on the rolls when actuated by the operator. The present invention is designed to improve wringers with relation to the safety features. Features and details of the invention will appear from the specification and claims.

A preferred embodiment of the invention is illustrated in the accompanying drawing as follows:—

15 Fig. 1 shows an end elevation, partly in section, on the line 1—1 in Fig. 2.

Fig. 2 a front elevation of the wringer, partly in section.

Fig. 3 an end view of a modification, said view being partly in section on the line 3—3 in 20 Fig. 4.

Fig. 4 a front view of the same modification, partly in section.

Fig. 5 a section on the line 5—5 in Fig. 2.

25 Fig. 6 a bottom view of one end of the top bar removed.

The frame has the base 1 with the side stiles 2, the base being of channel form and the side stiles hollow shape. Rolls 3 and 4 have shafts 30 5 and 6 and these shafts are journaled in bearing blocks 7 and 8 mounted in the side stiles. A pressure spring 9 operates on the top bearing blocks. It is adjusted by a screw 10 operating in a nut 11. The nut 11 is mounted in a top 35 bar 12. The top bar is of channel form with the ends closed and is adapted to cover the upper edges of the stiles.

Notches 13 are arranged in the side stiles. Hooks 14 extending from the sides 15 of latches 40 16 engage the shoulders 13. The latches are pivoted on pins 17 extending between the walls of the top. The latches are U-shaped in cross section, the top plate 18 of the latch having an extension 18a which engages an extension 19 on 45 the trip plate 20. The trip plate 20 has pivotal lugs 21 at its ends and these extend through openings 22 in brackets 23, the brackets being secured on the under-side of the top bar. In assembling the trip plate one bracket is secured, 50 the pivot lug of the plate moved into this bracket and then the opposite bracket is secured to the top plate. This bracket has a flange 24, the bottom of which forms a stop 25 for the extension 18a, and so limits the movement of the 55 latches 16. The latches are provided with pro-

jections 26 which are adapted to engage the tops of the stiles and assure the movement of the hooks into the notches, or under the shoulders 13. Springs 20a are provided at each side of the trip plate which yieldingly hold the trip plate in its set position. The trip plate 20 has upwardly extending projections 27 which extend through openings 28 in the top plate. They have reduced extensions 29 which form shoulders 30 and an operating member in the form of a 10 plate 31 is seated on these shoulders, the operating plate having perforations receiving the extensions 29. The upper ends of the extensions 29 are headed over, or provided with nuts 32 by which the top plate is rigidly secured on the extensions 27. The operating member, or plate 31 has projecting portions 31a extending to the front and back of the extensions 27 and connecting portions, or rails 31b connecting the portions 31a. These rails form the parts immediately engaged 20 by the operator to trip the release.

In the operation of the device when the operating plate 31 is tilted on either side of the wringer this swings the trip plate 20 with it carrying the trip extensions 19 off the extensions 18a thus releasing the latches. The top then yields and moves upwardly in response to the pressure of the spring and this movement relieves the rolls of the pressure of the spring. The latch mechanism by reason of the fact that the hook 30 is practically below the pin 17 puts almost no pressure on the trip extensions 18a and 19 so that the release is very sensitive. On the other hand, the engaging surface of the hook 14 is so shaped that when the latch is released by the trip plate there is an immediate movement of the latch to release the hooks. 35

In the structure shown in Figs. 3 and 4 the releasing mechanism as a whole is identical with that of Figs. 1 and 2 except that the operating member 34 extends over the top bar forming a skirt for the top bar, this skirt preferably extending around the ends of the top bar and these ends stiffening the skirt and at the same time adding to the finished appearance of the 45 wringer.

What I claim as new is:—

1. In a wringer, the combination of a frame having a top bar; rolls mounted in the frame; pressure means between the top bar and the 50 rolls for exerting pressure from the top bar to the rolls; and a safety release device for the means comprising a member pivotally mounted on the top bar with its axis at the top of the top bar and extending longitudinally thereof, said bar 55

- extending over the top bar and forming a skirt each side thereof and around the end of the top bar;
2. In a wringer, the combination of a frame including a hollow top bar; rolls mounted in the frame; pressure means for the rolls; a safety release for the means comprising a trip member on the inside of the bar and pivoted on the top bar with the pivot extending longitudinally of the top bar; an operating member; and a connection extending through the top bar uniting the trip member and the operating member, said operating member extending to each side of the top bar and forming a skirt therefor, said skirt extending around the ends of the top bar.

3. In a wringer, the combination of a frame comprising a base and stiles; a top bar on the stiles, said top bar being of channel form; a pressure means exerting pressure from the top bar on the rolls; a release device for releasing the pressure of the means having an operating member pivotally mounted on a longitudinal axis within the top bar and pivotally movable cross-ways of the top bar to effect a release; and an operating bar extending longitudinally of the wringer above the top bar and rigidly connected through the top bar with the operating member.
